WITNESS:

INVENTOR
BY *Victor J. Evans*

ATTORNEY

UNITED STATES PATENT OFFICE.

LUTHER A. NORLAND, OF SANFORD, COLORADO.

SICKLE HOLDER.

Application filed August 28, 1922. Serial No. 584,897.

To all whom it may concern:

Be it known that I, LUTHER A. NORLAND, a citizen of the United States, residing at Sanford, in the county of Conejos and 5 State of Colorado, have invented new and useful Improvements in Sickle Holders, of which the following is a specification.

The principal object of this invention is to provide means for holding a sickle of a 10 mowing machine while the same is being sharpened on a grindstone or the like, such means permitting the sickle to be adjusted so that all the knives thereon can be brought into engagement with the grindstone.

15 Another object of the invention is to place the holding means for the sickle on a member which is swiveled to a supporting member.

This invention also consists in certain 20 other features of construction and in the combination and arrangement of the several parts, to be hereinafter fully described, illustrated in the accompanying drawings and specifically pointed out in the appended 25 claim.

In describing my invention in detail, reference will be had to the accompanying drawings wherein like characters denote like or corresponding parts throughout the several views, and in which:—

Figure 1 is an elevation.

Figure 2 is a longitudinal section through the support.

Figure 3 is a section on line 3—3 of 35 Figure 1.

In these views 1 indicates a plate which is adapted to be secured to a ceiling or other support by screws or the like. This plate is provided with a threaded hole 2 for receiving the threaded end of a rod 4 which supports a tube 5 which surrounds the rod. The rod and tube are also supported by the brace 6. The rod passes through a T-coupling 7, one end of which engages the 40 end of the tube and the coupling is held in place by a nut and washer 8 on the end of the rod. Thus the tube and coupling have rotary movement on the rod. Pipes 9 have their inner ends threaded to engage the T-coupling 45 and the outer ends of these pipes have secured thereto the stops 10. A hanger 11 is slidably supported on each pipe, each hanger consist-

ing of a frame 12 carrying a sheave 13 which engages the pipe and to which is swiveled a yoke-shaped frame 14 by the rivet 15, said 55 yoke-shaped frame carrying a pulley 16. A chain 17 passes over each of the pulleys 16, a spring clip 18 of U-shape, being connected with one end of the chain and the other end carrying a weight 19 which is 60 provided with an extension 20 having an eye therein to receive the other part of the chain. The clips 18 are adapted to engage the sickle, which is shown at A.

From the above it will be seen that the 65 sickle can be moved longitudinally on the pipes 9 by the sheaves in the frames rolling on said pipes. It can also be turned at various angles by turning the tube and coupling on the rod 4. The sickle can also be raised 70 and lowered by means of the chains and weights. Thus it will be a simple matter to bring all the knives on the sickle into engagement with the grindstone.

It is thought from the foregoing description 75 that the advantages and novel features of my invention will be readily apparent.

I desire it to be understood that I may make changes in the construction and in the combination and arrangement of the several 80 parts, provided that such changes fall within the scope of the appended claim.

What I claim is:—

A device of the character described including a plate adapted to be secured to the 85 ceiling of a structure, a rod depending from the plate, a tube arranged on the rod for a rotary movement, a V-shaped bracket receiving the tube and having its ends secured to the ceiling, a horizontal tubular standard 90 carried by the lower end of the rod, stops at the opposite ends thereof, carriages movable on the tubular standard, flexible elements carried by the carriages, clips carried by one end of each of the flexible elements 95 for engagement with an object to be supported and weights provided with eyes and secured on the opposite ends of the flexible elements and having slidably engagement with the flexible elements through the 100 medium of the eyes.

In testimony whereof I affix my signature.

LUTHER A. NORLAND.
